(57) **CLAIM**

The ornamental design for a blood pressure measuring apparatus, as shown and described.

DESCRIPTION

FIG. 1 is a front view illustrating our new design for a blood pressure measuring apparatus;

FIG. 2 is a rear view of the blood pressure measuring apparatus of FIG. 1;

FIG. 3 is a top view of the blood pressure measuring apparatus of FIG. 1;

FIG. 4 is a bottom view of the blood pressure measuring apparatus of FIG. 1;

FIG. 5 is a right side view of the blood pressure measuring apparatus of FIG. 1;

FIG. 6 is a left side view of the blood pressure measuring apparatus of FIG. 1;

FIG. 7 is an enlarged perspective view of the blood pressure measuring apparatus of FIG. 1; and,

FIG. 8 is an enlarged partial view of the blood pressure measuring apparatus of FIG. 1 delineated by line 8—8 in FIG. 1.

The broken lines illustrating a cuff in connection with the blood pressure measuring apparatus are for illustrative purposes only and form no part of the claimed design.
